UNITED STATES PATENT OFFICE

LEE B. GREEN, OF LAKewood, OHIO, ASSIGNOR TO THE GLOBE MACHINE & STAMPING COMPANY, OF CLEVELAND, OHIO, A CORPORATION OF OHIO

DESIGN FOR AN AUTOMOBILE RADIATOR SHELL WITH LOUVER TYPE GRILLE

Application filed March 21, 1932. Serial No. 43,242. Term of patent 7 years.

To all whom it may concern:

Be it known that I, LEE B. GREEN, a citizen of the United States, residing at Lakewood, in the county of Cuyahoga and State of Ohio, have invented a new, original, and ornamental Design for an Automobile Radiator Shell with Louver Type Grille, of which the following is a specification, reference being had to the accompanying drawing, forming part thereof.

In the drawing, Fig. 1 is a front elevation of an automobile radiator shell with louver type grille, showing my new design.

Fig. 2 is a horizontal section, taken on the line 2—2 of Fig. 1.

Figure 3 is a vertical sectional view on the line 3—3 of Figure 1.

As shown in the drawing, the presented grille assembly comprises parallel and uniformly spaced louver bars, with the bars consecutively decreasing in width from the center to each side of the assembly, thereby producing a novel ornamental effect in which the louver bars appear as if they had their forward edges disposed in two rearwardly diverging planes.

I claim:

The ornamental design for an automobile radiator shell with louver-type grille, as shown and described.

LEE B. GREEN.
